UNITED STATES PATENT OFFICE.

MAX RACHLIN, OF BROOKLYN, NEW YORK.

DESIGN FOR A PIPE SUPPORT.

Application filed November 12, 1926. Serial No. 19,694. Term of patent 14 years.

To all whom it may concern:

Be it known that I, MAX RACHLIN, a citizen of the United States, residing at Brooklyn, in the county of Kings and State of New York, have invented a new, original, and ornamental Design for a Pipe Support, of which the following is a specification, reference being had to the accompanying drawings, forming part thereof.

Figure 1 is a front elevation of a pipe support, showing my new design; Fig. 2 is a top plan view thereof; and Fig. 3 is a section taken on line 3—3 of Fig. 1.

I claim:

The ornamental design for a pipe support, as shown.

MAX RACHLIN.
